(57) **CLAIM**

I claim the ornamental design for a T-slot bolt, as shown and described.

DESCRIPTION

FIG. 1: is a perspective top, front and first side view of a T-slot bolt showing the design applied thereto;

FIG. 2: is a front elevational view thereof;

FIG. 3: is a first side view thereof;

FIG. 4: is a rear elevation view thereof;

FIG. 5: is a second side view thereof;

FIG. 6 is a bottom elevation view thereof; and,

FIG. 7 is a top plan view thereof.
